Specification for Design.

Patented Dec. 13, 1921.

Application filed July 15, 1921. Serial No. 485,106. Term of patent 14 years.

To all whom it may concern:

Be it known that I, FREDERICK G. PROCTOR, a citizen of the United States, residing at Detroit, in the county of Wayne and State of Michigan, have invented a new, original, and ornamental Design for a Truck-Cab, of which the following is a specification, reference being had to the accompanying drawing, forming part thereof.

Figure 1 is a perspective view of a truck-cab, showing my new design, Fig. 2 is a rear

elevation and Fig. 3 is a side elevation of the same.

I claim:

The ornamental design for a truck cab, as shown.

In testimony whereof, I sign this specification in the presence of two witnesses:

FREDERICK G. PROCTOR.

Witnesses:

S. E. THOMAS,
IDA GOREN.
